SAFETY RAZOR BLADE

Filed Nov. 15, 1930

Inventor

Ralph E. Thompson
By his Attorney *J.W. Fenner*

UNITED STATES PATENT OFFICE

RALPH E. THOMPSON, OF BROOKLINE, MASSACHUSETTS, ASSIGNOR TO GILLETTE SAFETY RAZOR COMPANY, OF BOSTON, MASSACHUSETTS, A CORPORATION OF DELAWARE

SAFETY RAZOR BLADE

Application filed November 15, 1930. Serial No. 496,025.

This invention relates to safety razors and relates more particularly to a blade for safety razors of the Gillette type.

An object of the invention is to provide a safety razor blade having a yielding edge.

Another object of the invention is to provide a safety razor blade having vibratory shaving edges.

Another object of the invention is to separate the sharpened edges of a safety razor blade from other portions of the blade which are subjected to softening heat treatment.

While the rigidly positioned sharpened edges of safety razor blades have been entirely satisfactory to the majority of safety razor users, others prefer blades having flexible sharpened edges which will yield to the skin and which will vibrate during the shaving operation. It is the purpose of the present invention to provide such a blade for safety razors.

According to this invention the flexible cutting edges are on narrow strips, almost completely severed by slots from the body portion, leaving the cutting edges very flexible and free to yield and vibrate.

In one embodiment of the invention, each flexible cutting edge is joined to the body portion of the blade by a central narrow connecting neck portion, the cutting edge portions being separated from the body portion by slots on each side of the connecting neck portions.

In another embodiment of the invention, the cutting edges are mounted on narrow strips which are connected to the central body portion, one at one end of the blade and the other at the other end of the blade, and on the opposite side, with narrow slots separating the cutting edge portions from the central body portion except for the narrow connecting portions at the ends of the blade.

In still another embodiment of the invention, the cutting edge portions are substantially separated from the central body portion by narrow slots, which extend almost to the end of the cutting edges, the cutting edge portions, however, being connected around the slots to the body portion. The slots in this embodiment of the invention

serve another useful function in that where it is desired to heat treat the central portion of the body of the blade to make it soft, so as to increase its elastic limit, the slots which substantially isolate the cutting edge portions from the body of the blade, prevent the softening heat from reaching and affecting the tempered cutting edge portions.

The invention will now be explained with reference to the drawings which illustrates the three embodiments of the invention above described:

Fig. 1 of the drawings is a plan view of a safety razor blade, according to this invention, having the cutting edge portion separated from the body portion except at a narrow central connecting portion;

Fig. 2 is a view of a safety razor blade, according to this invention, each of the cutting edge portions of which are attached to the body of the blade only by a single narrow end connecting portion, and

Fig. 3 is a view of a safety razor blade, according to this invention, having the cutting edge portions separated from the body portion by narrow slots which extend almost to the ends of the blade.

Referring now to Fig. 1 of the drawings, the blade there shown has a central body section 5 and the two flexible cutting edge portions 6. The cutting edges 7 are formed on the outermost portions of the portions 6. The strips 6 are attached to the body 5 of the blade by means of the connecting neck portions 8, and are separated from the body portion 5, except for the narrow connecting portion, by means of the narrow slot 9. The blade is adapted to be mounted in the well known manner by means of the positioning openings 9.

The cutting edge portions are seen to be very flexible and free to yield during the shaving operation. The edges of the blade, when clamped in its holder, are adapted, as is well known, to have their upper portions contact with the edges of the cap member which bends the cutting edge portions down into their proper position relative to the edges of a guard member of a holder. Since the cutting edge portions of the blade are flexible

and free to vibrate, they will yield to the pressure of the skin during the shaving operation and will vibrate as the edge of the blade is drawn across the face.

8 The embodiment of the invention shown by Fig. 2 has the narrow strips 10, on which the cutting edges 11 are formed, joined to the central body portion 12 by the end connecting portions 13, each narrow strip forming 10 the cutting edge portion, being attached to the central body portion at only one end, and it is preferred that the connecting portion 13 of one of the cutting edge strips be at the opposite end of the body portion of that of the other, as is clearly shown by Fig. 2. The blade is adapted to be positioned in its holder by means of the positioning apertures 14. When the blade is clamped in its holder, the cap portion, as has previously been explained, 20 contacts with the cutting edge portion just back of the cutting edge, and positions the cutting edge in its proper relation to the guard member of the holder. Since each cutting edge portion is free to vibrate, except 25 at one of its ends, the cutting edge portion will yield to the pressure of the flesh in shaving and is free to vibrate.

The embodiment of the invention shown by Fig. 3 consists of the blade having the 30 central body portion 15, the cutting edge portion 16, and the narrow slots 17 which are placed between the cutting edge portions 16 and the central body portion. The cutting 35 edge portions are connected to the central body portions by means of the narrow connecting portions at each end of the slot 17 so that the cutting edge portions are but little restrained in their movement by the central body portions, so that the cutting edge 40 portions are free to yield to the flesh in shaving and to vibrate.

The structure shown by Fig. 3 has another 45 advantage in that the central body portion may be softened by heat treatment without the heat reaching the tempered cutting edge portions. It may be desirable to soften the central portion of a safety razor blade, as indicated by the shaded lines of Fig. 3. This softening is accomplished after the blade is 50 tempered by heating the shaded portions. The purpose of the softening is to increase the elastic limit of the metal so that the strains which occur in the bending of the blade, while being clamped in its holder, may 55 be easily absorbed by the softened portions where the bending of the blade occurs.

Whereas one or more embodiments of the invention have been described for the purpose of illustration, it should be understood 60 that the invention is not limited to the exact details described, as many departures may be made by those skilled in the art without departing from the spirit of the invention.

What is claimed is:

65 1. A safety razor blade having a sharpened

edge portion and a body portion, said sharpened edge portion being attached to said body portion by a narrow centrally placed neck and being separated from said body portion on each side of said neck by longitudinal slots 70 located between the sharpened edge and the center of the blade.

2. A safety razor blade having opposed longitudinal sharpened edge portions and a central body portion, said sharpened edge portions being attached to said body portion by a narrow centrally placed neck and being separated from said body portion on each side of said neck by longitudinal slots located 75 between the sharpened edge and the center of the blade.

3. A safety razor blade having a sharpened edge portion and a body portion, said sharpened edge portion being attached to said body portion by a narrow neck at one end of said edge portion, the remainder of said edge portion being spaced from said body portion by a longitudinal slot.

4. A safety razor blade having opposed longitudinal cutting edges and a body portion, said cutting edge portions being attached to said body portion each by means of a narrow neck at one end and being spaced from said body portion along the remainder 90 of the cutting edge portions, and being separated from said body portion by longitudinal slots.

5. A safety razor blade having a longitudinal sharpened edge portion and a longer body portion, the body portion being separated from the cutting edge portion by means of a longitudinal open-ended slot extending substantially as long as the cutting edge.

6. A safety razor blade having opposed longitudinal cutting edges and a central body portion longer than said cutting edge portions, each of said cutting edge portions being separated from said body portion by means of a longitudinal open-ended slot substantially as long as its cutting edge.

7. A safety razor blade having opposed longitudinal cutting edges and a central body portion longer than said cutting edge portions, each of said cutting edge portions being separated from said body portion by means of a longitudinal open-ended slot substantially as long as its cutting edge, the central body portion being heat treated, the slot preventing the heat from affecting the 110 temper of the cutting edges.

Signed at Boston, Massachusetts, this 14th day of November, 1930.

RALPH E. THOMPSON.
